Patented July 31, 1917.

UNITED STATES PATENT OFFICE.

CHARLES W. LORD, OF PROVIDENCE, RHODE ISLAND, ASSIGNOR TO WILLIAM H. CRANSTON, OF CRANSTON, RHODE ISLAND.

SNAP-FASTENER.

1,235,213.

Specification of Letters Patent. Patented July 31, 1917.

Application filed November 4, 1916. Serial No. 129,622.

To all whom it may concern:

Be it known that I, CHARLES W. LORD, a citizen of the United States, residing at Providence, in the county of Providence and State of Rhode Island, have invented a new and useful Improvement in Snap-Fasteners, of which the following is a specification.

This invention relates to certain new and useful improvements in snap fasteners, and pertains more particularly to snap fasteners employed in connection with gloves and garments, and the method of making same.

The primary object of the invention is to provide a method of making the female members of snap fasteners from a single blank and from a single uniform thickness of sheet metal, which method can be easily and quickly practised so as to expeditiously and economically form the members.

Further, the invention aims to provide a method in which a series of blanks are successively and initially formed in a continuous manner and then separated to complete the formation of the fasteners.

Other and further objects will later herein appear and be manifested in the course of the following description.

In the drawings—

Figure 1 is a vertical sectional view of a pair of rolls for initially acting on the strip of metal.

Fig. 2 is a fragmentary plan view of the strip after having been acted upon by the rolls.

Fig. 3 is a section on the line 3—3 of Fig. 2.

Fig. 4 is a plan view of one of the fasteners upon completion, and

Fig. 5 is a section on the line 5—5 of Fig. 4.

The invention is practised by use of a pair of rolls 1, and 2, the surfaces of which are so configured or cut as to form circular raised portions or ribs 3 and 4 on the sheet metal strip S. Preferably in following the method, a long strip is used upon which a series of the ribs are formed as shown in Fig. 2, by passing the strip continuously between the rolls. The rolls are also so shaped and related as to form thin webs 5 and 6 between the circular raised portions or ribs, while the ribs themselves are thickened

and are preferably of substantially circular cross-section. 55

The blank having assumed the form depicted in Fig. 2, is next placed in a press which has suitable cutters so as to cut-out or remove the central thin web 6, and to trim the peripheral edges, and at the same time 60 to form the cut-outs 7. These cut-outs 7 provide the fastener with the fingers or parts 8 which serve to flexibly connect the central rib 3 to the outer rib 4. As will be understood the central rib 3 is now in the 65 form of arc-shaped parts or separate jaws which grip the male member of the fastener when the latter is introduced through the opening 9.

Finally, the fasteners are placed in a rumble or the like and tumbled to remove the rough edges which are sometimes present incident to the cutting. 70

It will be apparent from the foregoing that the invention involves practically but 75 two steps, namely, first the formation of the ribs and thinned webs, and second the cutting away of the inner or central web and the slitting of the central rib and the outer web to form the usual resilient fingers which 80 grip the head forming the male fastener. Since the invention is practised with a blank possessed of uniform thickness, and any number of ribs may be formed thereon, depending on the length of the blank, it will 85 be apparent that a great saving of time is effected, since after the formation of the ribs, the blank can be fed step-by-step into a cutting press or the like to effect the cutting operations mentioned in the foregoing. 90

Having thus described my invention, what I claim as new and desire to secure by Letters Patent is—

1. The herein-described method of making snap fasteners, which consists in first 95 passing a blank between two rolls to form same with a central web and inner and outer circular thickened ribs connected by a second web, then in removing the central web and cutting the other web and the inner rib 100 to form a series of fingers which flexibly support the cut inner rib.

2. The herein described method of making snap fasteners which consists in forming inner and outer circular ribs and a thin central 105 web and a thin connecting outer web on a

piece of metal, then in removing the central part of the web and cutting the outer web and the inner rib whereby to form a divided inner rib connected to the outer rib by a series of spaced fingers.

3. The herein described method of making snap fasteners, which consists in forming raised circular inner and outer ribs on a sheet metal blank and in thinning the blank to form an inner web and an outer web between the inner and outer ribs, and then in removing the inner part of the web and cutting the outer rib and outer part of the web to form a series of fingers connecting the cut inner rib to the outer rib.

4. The herein described method of making snap fasteners which consists in subjecting a blank of uniform thickness to pressure to form raised inner and outer ribs thereon with an inner web and an outer web each of less thickness than that of the origi-

nal blank, and finally in removing the central part of the web and cutting the inner rib and outer part of the web to form fingers.

25

5. The herein-described method of making snap fasteners, which consists in forming inner and outer ribs respectively alined on the opposite faces of a blank and an inner web and an outer connecting web, and then in removing the inner part of the web and the material surrounding the outer ribs and in cutting the inner rib and outer part of the web to form fingers.

30

In testimony whereof I have signed my name to this specification in the presence of two subscribing witnesses.

CHARLES W. LORD.
